US00D997041S

(12) **United States Design Patent** (10) **Patent No.:** **US D997,041 S**
Wang et al. (45) **Date of Patent:** **** Aug. 29, 2023**

(54) **INTELLIGENT DEVICE FOR RIDING
INSTEAD OF WALKING**

(71) Applicant: **Beijing Infinitics Technology Co., Ltd.**,
Beijing (CN)

(72) Inventors: **Zhipeng Wang**, Beijing (CN); **Zhixing Li**, Beijing (CN); **Yujie Li**, Beijing (CN)

(73) Assignee: **Beijing Infinitics Technology Co., LTD.**, Beijing (CN)

(**) Term: **15 Years**

(21) Appl. No.: **29/806,264**

(22) Filed: **Sep. 1, 2021**

(30) **Foreign Application Priority Data**

Jul. 21, 2021 (CN) 202130465368.6
Jul. 21, 2021 (CN) 202130465766.8

(51) **LOC (14) Cl.** **12-12**

(52) **U.S. Cl.**

USPC **D12/128**

(58) **Field of Classification Search**

USPC D12/128, 130, 131
CPC A61G 5/04; A61G 5/041-047; A61G
2005/048

Primary Examiner — Charles D Hanson

(74) *Attorney, Agent, or Firm* — Loza & Loza LLP;
Michael F. Fedrick

(57) **CLAIM**

The ornamental design for an intelligent device for riding instead of walking, as shown and described.

DESCRIPTION

FIG. 1 is a front view of our new design;

FIG. 2 is a back view thereof;

FIG. 3 is a left-side view thereof;

FIG. 4 is a right-side view thereof;

FIG. 5 is a top view thereof;

FIG. 6 is a bottom view thereof;

FIG. 7 is a first perspective view thereof;

FIG. 8 is a second perspective view thereof; and,

FIG. 9 is a third perspective view thereof.

1 Claim, 9 Drawing Sheets
